CART FOR TRANSPORTING FOOD TRAYS AND THE LIKE

Robert H. MacKay, 1917 Cherry Blossom Lane,
Fort Wayne, Ind. 46805

Filed Aug. 18, 1965, Ser. No. 86,634

Term of patent 14 years

(Cl. D14—3)

FIG. 1

FIGURE 1 is a perspective view of the cart for transporting food trays and the like with one door in the open position;

FIGURE 2 is an end view thereof with the other end being of substantially the same configuration; and,

FIGURE 3 is a side view thereof with both doors closed and the other side of the cart being of substantially the same configuration.

I claim:

The ornamental design for a cart for transporting food trays and the like, as substantially shown and described.
